UNITED STATES PATENT OFFICE.

JOHN W. HAINES, OF FORT FAIRFIELD, MAINE.

SNOW-SCRAPER.

SPECIFICATION forming part of Letters Patent No. 378,307, dated February 21, 1888.

Application filed November 10, 1887. Serial No. 254,814. (No model.)

To all whom it may concern:

Be it known that I, JOHN W. HAINES, a citizen of the United States of America, residing at Fort Fairfield in the county of Aroostook and State of Maine, have invented certain new and useful Improvements in Snow-Scrapers; and I do hereby declare the following to be a full, clear, and exact description of the invention, such as will enable others skilled in the art to which it appertains to make and use the same, reference being had to the accompanying drawings, and to letters or figures of reference marked therein, which form a part of this specification.

15 My invention relates to certain new and useful improvements in snow-scrapers; and it consists in the novel construction and arrangement of the parts thereof, which will be more fully hereinafter described, and pointed out

20 in the claims.

The object of my invention is to provide a snow-scraper which is adapted for forming roadways or breaking snow-covered roads, the parts thereof being simple and effective in 25 their construction and operation, strong and durable, easily handled and readily understood, and of comparatively inexpensive manufacture. I attain this object by the construction illustrated in the accompanying drawings, 30 wherein like letters of reference indicate similar parts in the several views, and in which—

Figure 1 is a perspective view of my improved form of road or snow scraper. Fig. 2 is a top plan view thereof. Fig. 3 is a longitudinal vertical section thereof; Fig. 4, detail 35 perspective views of attachments to my improvement.

A indicates the side beams, which form the runners, which have two cross-beams, A', near 40 each end thereof and crossing the top portions to form braces. A central cross-beam, A'', is also provided, which has upwardly-projecting fulcrum-brackets a, which receive hand-levers B B, which are pivoted therein. The front 45 ends of the hand-levers B have links b secured thereto at one end, and at their opposite ends to links b', attached to movable scrapers C C.

The scrapers C are pivoted to the side bars, A, by a pivot-bar, C', passing through support- 50 ing-beams C'', arranged on the top forward

portions of the scrapers C, and through bearing-plates c, secured to the forward portion of the side beams or runners, A, under the front beveled ends of the said runners. The front ends of the said scrapers are provided with 55 metal bindings or sheathings C', which resist wear thereupon.

Mounted against the forward inclined ends of the runners A, and resting against the beams C', are fenders D, which are formed of 60 two pieces of material hinged at or about their central portion, so as to extend over the side of the machine, and are supported in adjustment at the sides by removable brace-strips E. When the said strips E are removed from the 65 side sections of the fenders, the same can be readily folded against the sides of the machine for purposes which will be readily apparent.

The scrapers are slotted at their rear portions, and the runners extend through said slots, and with outer strips, d, and the inner strips lying adjacent to the sides of the runners form guides for the vertical movement of the said scrapers. By forcing either one or 75 both of the levers B downward the scrapers C are raised and set in operative position. The fenders throw the snow to one side as it is loosened by the forward beveled ends of the scrapers. By this means hardened crusts of 80 snow may be readily broken and removed and a roadway quickly formed.

It will be understood that draft-power will be applied to my device by suitable means. The parts of the improvement being simple and 85 effective in their construction and operation, they will be readily understood and controlled.

The utility and adaptability of my improvement being obviously apparent, it is unnecessary to further enlarge upon the same herein. 90

Having thus described my invention, what I claim as new is—

1. The combination of the side boards forming runners, the adjustable scrapers, the hand-levers for adjusting said scrapers, and the fenders, constructed as set forth and arranged on the top of the scrapers against the forward ends of the runners, substantially as described. 95

2. The combination of the side runners having top, front, and rear cross-braces and a 100

central brace carrying fulcrum-brackets, hand-levers mounted in said brackets and having link-rods secured to the front ends, the slotted scrapers, to the rear portion of which the link-rods are also connected, the pivot-bar C', the beams C^c and d, the hinged fenders D, and the brace-strips E, substantially as described.

In testimony whereof I affix my signature in presence of two witnesses.

JOHN W. HAINES.

Witnesses:

RICHARD L. BAKEN,
MILES F. DAVY.
